US00D886385S

(12) **United States Design Patent** (10) **Patent No.:** **US D886,385 S**
(45) **Date of Patent:** **** *Jun. 2, 2020**

(54) **COSMETIC COMPACT**(71) Applicant: **Mary Kay Inc.**, Addison, TX (US)(72) Inventor: **Jenny DeMarco Staab**, Dallas, TX (US)(73) Assignee: **Mary Kay Inc.**, Addison, TX (US)

(*) Notice: This patent is subject to a terminal disclaimer.

(**) Term: **15 Years**(21) Appl. No.: **29/686,533**(22) Filed: **Apr. 4, 2019****Related U.S. Application Data**

(62) Division of application No. 29/627,410, filed on Nov. 27, 2017, now Pat. No. Des. 850,006.

(51) **LOC (12) Cl.** ..... **28-03**(52) **U.S. Cl.** **D28/83**

Primary Examiner — Jennifer Rivard(74) *Attorney, Agent, or Firm* — Norton Rose Fulbright US LLP(57) **CLAIM**

The ornamental design for a cosmetic compact, as shown and described.

DESCRIPTION

FIG. 1 is a top perspective view of a cosmetic compact; FIG. 2 is a front view of the cosmetic compact shown in FIG. 1;

FIG. 3 is a back view of the cosmetic compact shown in FIG. 1;

FIG. 4 is a right side view of the cosmetic compact shown in FIG. 1;

FIG. 5 is a left side view of the cosmetic compact shown in FIG. 1;

FIG. 6 is a top view of the cosmetic compact shown in FIG. 1;

FIG. 7 is a bottom view of the cosmetic compact shown in FIG. 1; and,

FIG. 8 is a bottom perspective view of the cosmetic compact shown in FIGS. 1.

1 Claim, 8 Drawing Sheets# US D886,385 S
